ELECTRIC SWITCH CONSTRUCTION

William H. Modrack, Toledo, Ohio

Application November 22, 1938, Serial No. 241,859

6 Claims. (Cl. 200--82)

This invention relates to electric switch construction, the primary object of the invention being to provide a pneumatically controlled switch which will be actuated by the weight of a vehicle passing over the control means thereof, for completing a circuit to operate a suitable audible or visible signal, as conditions may require.

An important object of the invention is to provide a switch of this character which will, with a single operation, operate to produce a double signal through the simple compression and release action of the device.

Another important object of the invention is to provide a signal which will be operated by a switch embodying but few parts, and one which will be exceptionally cheap to manufacture, due consideration having been given to the strength and durability of the structure.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawing:

Figure 1 is a side elevational view of a switch constructed in accordance with the invention.

Figure 2 is a vertical sectional view through the switch.

Figure 3 is a plan view of the switch, the cover plate thereof having been removed.

Referring to the drawing in detail, the switch comprises a box-like body portion indicated generally by the reference character 5, the body portion being formed with openings in its end, into which the unions 6 are extended.

As shown, these unions 6 are provided with bores 7 which have enlarged end portions 8 providing seats for the coiled springs 9 which are of lengths to extend appreciable distances within the body portion.

Positioned within the box-like body portion 5, is the switch base indicated by the reference character 10, the switch base being of a length to closely fit against the end walls of the body portion 5. The base 10 is provided with a longitudinal bore that has its ends threaded to receive the threaded ends of the unions 6, which secure the base 10 in position against lateral movement.

The base 10 is also provided with a central cut-out portion 11 that extends through the bore. Mounted for sliding movement within the bore of the base 10, is a rod 12 that carries pistons 13 and 14 at its ends, the pistons being of diameters 5 to closely fit within the bore of the body portion. The coiled springs 9 are of lengths to engage the outer ends of the pistons 13 and 14, to normally hold the pistons in the position as shown by Figure 2 of the drawing.

Secured to the base 10, is a plate 15 which is constructed of insulating material, the plate 15 being held in position by means of the screws 16. This plate 15 carries the contact member 17 which has connection with the wire 18 leading 15 through an opening in the side wall of the box-like body portion 5. In circuit with the base 10, is a plate 19 to which the wire 20 which also leads through an opening in the side wall of the box-like body portion 5, is connected. These wires 18 20 and 20, of course lead to a signal not shown, and which is necessarily in circuit with a suitable source of electricity supply.

Secured to the contact member 17, is an inverted U-shaped contact member indicated at 21, the arms of the contact member 21 being of lengths to extend into the path of travel of the pistons 13 and 14, as the pistons move longitudinally of the bore of the base 10.

Connected with each fitting 6, is a rubber tube 30 21 which in turn has connection with a rubber sack 22, the sacks 22 being closed at their outer ends.

A cover plate indicated by the reference character 23 closes the top of the box-like body portion, and affords means whereby the various elements of the switch may be readily inspected or repaired.

The operation of the switch is as follows: Assuming that the compressing action is directed 40 to the body portion of the switch from the right side rubber tubing. The air sealed within the tubing forces the piston to the left side of the body portion until the inner face of the right-hand section or piston has made contact on the 45 right-hand side of the inverted U-shaped contact member 21, thereby completing the circuit to the signal which is in circuit with the switch, and which is not shown in the present drawing.

The signal remains operative for the duration 50 of a few seconds, by which time the air has dissipated slowly through the space between the piston and the cylinder wall, due to the fitting of the piston to produce this result. The coiled spring at the extreme left has been contracted 55

under this pressure. Meanwhile the air after a few seconds time has seeped through the space between the cylinder wall and the piston to such an extent that the coiled spring at the left 5 functions and expands to its normal length, releasing the piston from its connection with the contact member 21, the piston returning to about its normal position. Up to this point the rubber tube 21 is still in its compressed position. However, upon the release action of the tube the air 10 is drawn back, bringing the piston to the right side of the body portion, contracting the right-hand coiled spring to such a point that the inner face of the left section of the piston has made its 15 contact on the left side of the inverted U-shaped contact member 21 for another few seconds of time making the second separate and distinct signal. Meanwhile, the air has again seeped through between the cylinder wall and the piston, 20 equalizing the pressure, the right-hand coiled spring expanding to its normal shape forcing the piston away from the contact with all parts returning to their normal or inactive positions. When the compression is entirely released the 25 piston returns to its normal position by the action of the coiled springs at both ends of the rod 12. It will of course be understood that if the compression action comes from the left side of the body portion, or through the tube connected with 30 the union at the left side of the body portion, the action as described will be reversed.

What is claimed is:

1. A pneumatically controlled switch comprising a switch base having a longitudinal bore, a contact member extending into the bore at a point intermediate the ends thereof, pistons operating within the bore, a rod connecting the pistons, means for directing air under pressure to either end of the bore moving the pistons to complete a circuit with the contact member, and yieldable means for normally urging the pistons to their inactive positions.

2. A pneumatically controlled switch comprising a switch base having a longitudinal bore, and having a central cut-out portion extending to the bore, pistons operating in the bore, a contact member extending into the cut-out portion

and disposed in the path of travel of the pistons, and means for directing air under pressure to the pistons moving the pistons longitudinally of the bore to engage the contact member completing a circuit, and springs for urging the pistons to their normal positions.

3. A pneumatically controlled switch comprising a base having a longitudinal bore, a contact member extending into the bore, spaced pistons operating in the bore, means for directing air under pressure to either end of the bore, moving the pistons longitudinally of the bore, said pistons adapted to engage the contact member completing a circuit, and means for returning the pistons to their normal positions when the air pressure is released.

4. A pneumatically controlled switch comprising a base having a longitudinal bore, pistons operating within the bore, a flexible tube connected with each end of the base and communicating with the bore and adapted to direct air under pressure to the bore moving the pistons when the flexible tube is compressed, and a contact member extending into the bore and adapted to be engaged by the pistons completing a circuit.

5. A pneumatically controlled switch comprising a base having a longitudinal bore, a rod having pistons at its ends, operating in the bore, a contact member extending into the bore and disposed in the path of travel of the pistons to be engaged by the pistons completing a circuit, and flexible tubes connected with the ends of the base and adapted to direct air under pressure to the bore moving the pistons longitudinally of the bore, when the flexible tube is compressed, and springs for returning the pistons to their normal positions.

6. A pneumatically controlled switch comprising a base, pistons operating in the base, a contact member disposed in the path of travel of the pistons, and adapted to be engaged by the pistons, completing a circuit, flexible tubes connected with the base and adapted to direct air under pressure to the pistons when the tubes are compressed, and means for returning the pistons to their normal positions.
